Edmund Mason
Sellers Patent

The Schedule is placed in the Sellers Patent and making part of the same, containing a description in the words of the said Edmund Mason himself, of his improvement in the Threshing Machine.

The frame is constructed by two bed pieces, two posts, and two side pieces. The bed pieces are about four feet long, the posts about two feet, and are placed in the back part of the bed pieces. The side pieces are about twelve inches wide, and about four feet six inches long, the front ends of which are attached to the bed pieces. The back post is confined to the top of the posts. The incline is on an angle of about forty five degrees. Two cross pieces are placed on the posts and are in the forward part of the bed pieces, making the width two feet eight inches more or less, according to the power to be applied. The size is, for four horse power: sixteen inches wide is for one horse power. A cylinder is suspended about ten inches in front of the posts, the sole of which rests on the sides. The cylinder is formed by solid wood, or hollow, about eleven inches in diameter with the surface turned even.

About one fourth of the surface of the cylinder is covered with segments of wrought iron, iron about four inches long, with wrought iron hoops within about three inches of each other, the segments of iron being deformed that the hoops pass into the ends of each about one half inch. Projections being in rows on each segment about one half inch from the base.

Two top pieces are placed on the side pieces over the sole of the cylinder, and the two side pieces at the back part form the entrance for the unthreshed grain. A piece of iron bars with the edges up is placed under the cylinder covering about twelve inches of the cylinder. A cover is put upon the top over the cylinder to prevent the dust or chaff from rising, and a ladder on the back part of the entrance about twelve inches high to prevent the unthreshed grain from passing over the cylinder. A table is placed at the back part of the machine.

1584

when in use, of the height of the top of the piston, a little below the centre of the cylinder. The parts claimed by me in this machine are the segments and hoops of the cylinder so formed as to make a complete surface of great strength without the use of iron, or metal, and also the form of the frame for a horseless and convenient

car.
